(57) **CLAIM**

The ornamental design for a safety label assembly, as shown and described.

DESCRIPTION

FIG. 1 is a front elevation view of my safety label assembly; FIG. 2 is a side elevation view of the safety label assembly of FIG. 1;

FIG. 3 is a reduced scale front elevation view of my design shown in a window screen environment or condition of use; and,

FIG. 4 is illustrates an enlarged fragmentary view of the safety label assembly of FIG. 3.

The broken lines in the drawings represent environmental structure only and form no part of the claimed design.
